Primary Examiner—Louis S. Zarfas*Assistant Examiner*—Robert A. Delehanty*Attorney, Agent, or Firm*—Rosenberg, Klein & Bilker[57] **CLAIM**

The ornamental design for a potato skin stripping mitten, as shown and described.

DESCRIPTION

FIG. 1 is a perspective view of a potato skin stripping mitten, showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines shown in FIGS. 1, 4 and 5 represent stitching.
